CLAIM

We claim the ornamental design for a battery pack receiving area and connection terminals for a low current draw device, as shown and described.

DESCRIPTION

FIG. 1 is a front perspective view of a battery pack receiving area and connection terminals for a low current draw device of the present invention.

FIG. 2 is a top view of the battery pack receiving area and connection terminals of FIG. 1.

FIG. 3 is a left side view of the battery pack receiving area and connection terminals of FIG. 1.

FIG. 4 is a left side cross-sectional view of the battery pack receiving area and connection terminals of FIG. 1 along sectioning line 4—4 (shown in FIG. 2).

FIG. 5 is a right side cross-sectional view of the battery pack receiving area and connection terminals of FIG. 1 along sectioning line 5—5 (shown in FIG. 2).

FIG. 6 is a rear cross-sectional view of the battery pack receiving area and connection terminals of FIG. 1 along sectioning line 6—6 (shown in FIG. 2).

FIG. 7 is a front cross-sectional view of the battery pack receiving area and connection terminals of FIG. 1 along sectioning line 7—7 (shown in FIG. 2).

FIG. 8 is a top cross-sectional view of the battery pack receiving area and connection terminals of FIG. 1 along sectioning line 8—8 (shown in FIG. 3); and,

FIG. 9 is a bottom cross-sectional view of the battery pack receiving area and connection terminals of FIG. 1 along sectioning line 9—9 (shown in FIG. 3).

The portions of the design shown in broken lines are included for the purpose of illustrating environment and form no part of the claimed design. The portions of the design shown in broken lines having unequal segments illustrate the boundary of the claimed design and form no part of the claimed design.
